UNITED STATES PATENT OFFICE

167,339

HELMET FOR PROTECTION AGAINST LOW TEMPERATURES

Vaito K. Eloranta, Boston, Mass., assignor to the United States of America as represented by the Secretary of the Army

Application February 7, 1952, Serial No. 18,433

Term of patent 3½ years

(Cl. D83—1)

To all whom it may concern:

Be it known that I, Vaito K. Eloranta, a citizen of the United States, residing at Boston, in the county of Suffolk and State of Massachusetts, have invented a new, original, and ornamental Design for a Helmet for Protection Against Low Temperatures, of which the following is a specification, reference being had to the accompanying drawings, forming a part thereof.

Figure 1 is a perspective view of a helmet for protection against low temperatures, embodying my new design;

Figure 2 is a side elevation of the helmet as viewed from the side opposite to that shown in Figure 1, and,

Figure 3 is a rear elevation of the helmet.

The dominant features of the design are shown in full lines, in the drawings.

I claim:

The ornamental design for a helmet for protection against low temperatures, substantially as shown and described.

VAITO K. ELORANTA.
